UNITED STATES PATENT OFFICE.

JOHN C. WARD, OF QUINCY, MASSACHUSETTS, ASSIGNOR TO WINTHROP CORPORATION,
OF BOSTON, MASSACHUSETTS, A CORPORATION OF MASSACHUSETTS.

HOLLOW BODY OF FIBROUS MATERIAL.

1,264,351.

Specification of Letters Patent. Patented Apr. 30, 1918.

Application filed January 28, 1918. Serial No. 214,110.

To all whom it may concern:

Be it known that I, JOHN C. WARD, a citizen of the United States, and a resident of Quincy, in the county of Norfolk and State 5 of Massachusetts, have invented an Improvement in Hollow Bodies of Fibrous Material, of which the following description, in connection with the accompanying drawings, is a specification, like characters 10 on the drawings representing like parts.

This invention relates to a hollow body composed of a strip of fibrous material wound into a plurality of overlapping convolutions which are cemented together, and 15 substantially such as shown and described in U. S. Patent No. 1,156,193 granted to me October 12, 1915, and has for its object to improve hollow fibrous bodies of the character described, and especially conical hollow 20 bodies, whereby they are rendered more durable, stronger and more efficient in operation.

To this end, the hollow body is provided at its base or lower end with a cuff of fibrous 25 material, which is folded over or under the lower edge of the hollow body and is extended up on the inner and outer surfaces of said body and cemented thereto, and when the hollow body is made in the form of a 30 cone, the upper end thereof is rounded over toward the axial center of the cone and burnished to form a smooth, rounded, external surface at the upper end of the cone to facilitate unwinding of the thread, yarn or 35 the like from the same and prevent breaking thereof.

The particular features of the invention will be pointed out in the claims at the end of this specification.

40 Figure 1 is an elevation of a cone embodying this invention.

Fig. 2, a section on an enlarged scale of the base portion of the cone to clearly illustrate the cuff thereon, and

45 Fig. 3, an enlarged section of the upper end of the cone to illustrate the rounded over external surface thereof.

Referring to the drawings *a* represents a 50 hollow body in the form of a cone, which is open at its upper and lower ends *b*, *c*, and which is composed of a strip of fibrous material, such as paper, which strip is folded at one end to form a folded portion 10 and a body portion 12 of greater width than

said folded portion, and which strip is 55 wound into a plurality of overlapping convolutions with the folded body portion 10 of one convolution cemented to the unfolded body portion 12 of a preceding convolution by a layer or coating of adhesive material applied to the fibrous strip before the latter is folded and indicated by the heavy line 13. The hollow cone as thus far described is and may be substantially the same 60 as shown and described in the patent referred to and is not herein claimed broadly.

The present invention has for its object to improve the cone *a* so as to render the 65 same more durable, stronger and more efficient in operation, especially when the yarn, 70 thread or the like is unwound.

To this end, the base portion *c* of the cone is provided with a cuff *d* of relatively thin paper or like fibrous material, which is folded over or under the lower edge of the cone 75 and is extended up on the inner and outer surfaces of said cone to form side walls 20, 21, of a channeled shaped cuff having its bottom wall 22 engaged with the lower edge of the cone, and the said cuff is secured in 80 fixed relation to the cone by cement or other adhesive.

In this manner the convolutions at the base of the cone are practically sealed by a protective layer or cuff, which prevents liability of the convolutions at the base of the cone being accidentally opened up or separated in handling or transportation, which if allowed to take place would permit the 85 helically wound strip comprising the cone 90 to be unraveled and the cone to be rendered useless or at least unfitted for practical service until repaired.

In addition, the cuff serves to reinforce the cone at its base and thereby greatly 95 strengthen the same, and enables it to withstand comparatively severe usage in handling.

The upper end *b* of the cone is provided with a smooth, outer surface 25, which is 100 rounded in toward the axial center of the cone, and which may be effected by applying a suitable tool to the end of the cone while the latter is revolving. The rounded-in, 105 smooth outer surface 25 offers no obstruction to the yarn, thread or the like when the latter is being unwound from the cone, which is highly desirable in practical use, as

breakage of fine yarns, silks, etc., are avoided with the attending loss in material, and time for repairing breaks in the yarn.

Claims.

- 5 1. A hollow body composed of a strip of fibrous material wound into a plurality of overlapping convolutions cemented together, and a cuff of fibrous material folded over one end of the hollow body and adhesively 10 affixed to the inner and outer surfaces thereof.
- 15 2. A hollow conical body composed of a strip of fibrous material wound into a plurality of overlapping convolutions which are cemented together and having the uppermost convolutions of the conical body rounded in toward the axial center of the said conical body to provide the latter at its 20 upper end with a smooth outer rounded-in surface and having at its lower end a cuff

of fibrous material folded over the lower end of said conical body and adhesively affixed to the inner and outer surfaces thereof.

- 25 3. A hollow conical body composed of a strip of fibrous material folded over at one edge and wound into a plurality of overlapping convolutions which are cemented together with the folded body portion of one convolution cemented to the unfolded body 30 portion of a preceding convolution, and having the uppermost convolution rounded in toward the axial center of the conical body, and provided at its lower end with a cuff of fibrous material folded over the lower edge 35 of said conical body and adhesively affixed to the inner and outer surfaces thereof.

In testimony whereof, I have signed my name to this specification.

JOHN C. WARD.
